UNITED STATES PATENT OFFICE.

ESSYE K. POLLACK, OF NEW YORK, N. Y.

BUST CONFINER.

Application filed October 30, 1923. Serial No. 671,866.

This invention relates to new and useful improvements in surgical bandages and more particularly to a bust confiner, having for its principal object to provide a bust confiner which is hygienic in every respect.

Another object of the invention resides in the provision of a bust confiner adapted to be worn by women with large and heavy breasts, especially by women immediately following childbirth, when the breasts become weighty and have a tendency toward considerable pain.

It is a well known fact that women after childbirth experience great pain and suffering from dragging and heavy breasts and the application of liniment and massaging of the same seldom relieves the pain.

My improved invention has for its object to provide a bandage formed preferably of net or other similar porous material which is constructed in an improved manner to provide pockets for the support of the breasts so that the latter may maintain their normal position and yet be relieved of the dragging which causes great pain.

A further object of the invention resides in the provision of a bust confiner which lightly supports the breasts in a manner which prevents caking and inflammation, which may be quickly and easily applied to the body, comfortably worn and affords great relief to those who have suffered from the lack of an efficient support of this character.

A still further object of the invention is to provide a bust confiner of the above mentioned character which is simple in construction, inexpensive to manufacture and one which will be very efficient and useful in application to use.

With these and other objects in view my invention consists of the novel features of construction, combination and arrangements of parts as will be hereinafter referred to and more particularly pointed out in the specification and claim.

In the accompanying drawings forming a part of this specification and in which like numerals designate like parts throughout the same:—

Figure 1 is a perspective view of my bust confiner showing the same applied.

Figure 2 is a rear view thereof.

Figure 3 is a front elevation of my invention showing the same in a flat outstretched position.

Figure 4 is a plan view thereof.

Figure 5 is a vertical section taken on line 5—5 of Fig. 3.

Figure 6 is a perspective view of the blank 60 out of which my bust confiner is formed and showing the same in a folded position and wherein one portion of the blank is being stretched.

Figure 7 is a longitudinal section of the 65 blank as shown in Fig. 6 showing the same with one portion thereof stretched and

Figure 8 is a longitudinal section of the blank shown in Fig. 6 with the outer edges 70 brought together and stitched.

In the drawings wherein for the purpose of illustration is shown the preferred embodiment of my invention, the numeral 1 designates generally my bust confiner and is preferably formed of a piece of netting 75 although it is to be understood that any other suitable porous material may be used.

The bust confiner comprises a strip of material as described, folded over at approximately its median longitudinal center line 80 to form a two-ply material which is again folded upon itself near the median longitudinal center line of the two-ply material to form the pocket, the edges of the pocket being folded in and stitched and the ends 85

and center gathered and stitched, as indicated respectively, at 5, 8 and 11. In this manner, two pockets are formed in the device, the walls of the pocket nearer the body being of less height than the outermost walls 90 thereof. As the material used in connection with my bust confiner is formed of netting it will be seen that the stretching of the inner portion 3 may be easily accomplished and the necessary results obtained. In the 95 process of stretching the outer ends of the inner portion 3 the upper free edge thereof will become slightly curved as more clearly illustrated in Fig. 6 of the drawings.

After the outer ends of the inner portion 100 3 have been stretched to the desired degree, the free ends of the outer and inner portions respectively are brought together as shown more clearly in Fig. 8 of the drawings and are stitched at their upper edges by suitable stitching as shown at 4 and 4', the stitching

extending inwardly of the outer ends of the inner portion for a suitable distance. By securing the upper edges of the inner portion 3 at its outer ends to the outer portion 2 it will be seen that the inner portion 3 between the stitched ends will be slightly 105

110

bulged as more clearly shown in Fig. 8 of the drawings whereby the pockets for supporting and confining the breasts are formed.

The outer ends of the outer and inner portions respectively are gathered and suitable bands 5 extend transversely along the outer end edges thereof being stitched thereto by means of stitching as shown at 6 in the drawings. The purpose of these bands 5 is to 10 provide a means for receiving the fastening elements 7 and 8 respectively which extend along the outer edges of the band forming means for securing the ends of the bust confiner together when the same is applied 15 on the wearer. The fastening means may be of the well known hook and eye type and I do not wish to confine myself to the particular fastening means used as any other suitable fastening means may be substituted therefor. 20 It is to be further understood that the upper longitudinal edges of the outer and inner portions 2 and 3 respectively are folded inwardly upon themselves to provide the hems 9 and 10 respectively. This construction 25 is more fully shown in Fig. 5 of the drawings.

The outer and inner portions are also gathered centrally and suitable stitching 11 is adapted to hold the central gathered portions of the bust confiner in such a manner 30 as to provide the pockets 12 and 13 respectively on each side of the centrally stitched portion, said pockets being open at their upper edges, the openings extending from the centrally stitched portion 11 to the 35 adjacent end of the stitching 4, as clearly shown in Fig. 4 of the drawing.

These pockets 12 and 13 being open at the top enable the breasts to be received and confined within the pockets and will thereby 40 permit the breasts to maintain their normal position when the bust confiner is in use. By stretching the inner portion 3 as heretofore described the pockets 12 and 13 respectively which are formed as above described and clearly shown in the drawings 45 will have the proper fullness whereby the breasts may be comfortably supported in the pockets.

For the purpose of supporting the bust 50 confiner upon the body of the wearer, I provide suitable shoulder straps 14 and 15 respectively which are secured at their ends to the end hems 9 of the outer portion 2 by suitable stitching 16. The fastening means 55 7 and 8 respectively provide a means for se-

curing the outer ends of the bust confiner around the body of the wearer and are connected at the rear as shown in Fig. 2 of the drawings.

In providing a bust confiner of the above 60 mentioned character, which is especially adapted for use by women immediately after childbirth, the breasts will be properly supported and in a manner that will prevent the dragging of the breasts and which will 65 at the same time permit the free movement of the breasts and furthermore relieving the wearer of the bust confiner from severe pain.

By furthermore constructing a bust confiner of porous material the device is 70 rendered hygienic and does not require the use of expensive material in constructing the invention. The simplicity in which my bust confiner is constructed enables the same to be manufactured at a minimum cost and is 75 far more efficient than any of the bust confiners or breast supporters now in use, and does not require the use of a complicated structure in order to obtain the necessary results.

From the foregoing description of the construction of my improved apparatus, it will be seen that I have provided a simple, inexpensive and efficient means for carrying out the objects of the invention, and while 85 I have particularly described the elements best adapted to perform the functions set forth, it is obvious that various changes in form, proportion and in the minor details of construction may be resorted to, without 90 departing from the spirit or sacrificing any of the principles of the invention.

What I claim as new and desire to secure by Letters Patent is:—

A bust support comprising a strip of material folded longitudinally upon itself along a line lying beyond one side of the median longitudinal dimension of the strip to form a pocket having a relatively broad side wall and a relatively narrow side wall, the folds 95 being gathered transversely at their ends and longitudinally disposed lines of stitching extending inwardly from the gathered end edges of the folds and passing through the narrower fold at the longitudinal free edge 100 thereof, and through the broader folds along lines spaced from and approximately parallel with the free longitudinal edge thereof.

In testimony whereof I affix my signature.

ESSYE K. POLLACK.
